US00D995943S

(12) **United States Design Patent** (10) **Patent No.:** **US D995,943 S**
(45) **Date of Patent:** **** Aug. 15, 2023**

(54) **PET BREAST FEEDER**

(71) Applicant: **Zuling Yang**, Hunan Province (CN)

(72) Inventor: **Zuling Yang**, Hunan Province (CN)

(**) Term: **15 Years**

(21) Appl. No.: **29/799,364**

(22) Filed: **Jul. 14, 2021**

(51) **LOC (14) Cl.** **30-03**

(52) **U.S. Cl.**

USPC **D30/131; D30/121**

(58) **Field of Classification Search**

USPC ..... D30/121, 122, 129–133, 127, 124, 199, D30/119; 119/61.5, 51.01, 61.56, 51.03, 119/59, 62, 63, 51.5, 57.8, 74, 61.54, 119/61.55, 71, 61.57, 477, 454, 515, 464, 119/72.5, 77, 55, 710, 52.3, 56.1, 53, 119/52.1, 58, 76, 72; 312/204, 327; 248/151, 188, 222.14, 210, 102, 105, 106, 248/104, 311.2, 313, 316.5, 108, 302, 248/311.3; 108/153.1–157; 220/23.87, 220/630, 737, 743, 9.4, 495.01, 574, 212, 220/255, 23.83, 482, 758, 671, 769, 776, 220/904, 751, 770; 206/515, 524.5; D7/586, 543, 550.1, 587, 505, 584, 545, D7/500, 553.1–553.8, 546, 555, 556, 504, D7/565, 562, 602, 701, 702, 706, 707; D9/429; 43/109; D22/122; 99/430, 99/DIG. 15; D32/53; 222/465.1; 242/598.5; 224/414, 926; D12/411; D6/553, 450; D8/395, 396; D24/199, D24/198; 211/74, 75; D23/266; 273/394, 338, 127 B, 447, 127 R CPC A01K 5/00; A01K 5/01; A01K 5/0107; A01K 5/0114–0142; A01K 7/00; A01K 7/005; A01K 7/025; A01K 7/027; A01K 9/00; A01K 9/005; A01K 1/10; A47B 73/00; A47B 73/006; A47B 73/002; A47B 73/008; A61J 9/06; A61J 9/0607; A61J 9/0638; A61J 9/0676; A61J 9/0684; A61J

(57) **CLAIM**

The ornamental design for a pet breast feeder, as shown and described.

DESCRIPTION

FIG. 1 is a perspective view of the pet breast feeder showing my new design;

FIG. 2 is a perspective view from another angle thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict exemplary elements that are shown for illustrative purposes only and form no part of the design claim.

1 Claim, 8 Drawing Sheets
